UNITED STATES PATENT OFFICE.

EDWARD LESLIE, OF ORANGEVILLE, ONTARIO, CANADA, ASSIGNOR TO THE
LESLIE BROTHERS MANUFACTURING COMPANY, OF PATERSON, NEW
JERSEY.

SLIDE-VALVE.

SPECIFICATION forming part of Letters Patent No. 425,681, dated April 15, 1890.

Application filed January 24, 1889. Renewed September 23, 1889. Serial No. 324,709. (No model.)

To all whom it may concern:

Be it known that I, EDWARD LESLIE, of Orangeville, in the county of Dufferin, Province of Ontario, and Dominion of Canada, have invented a new and Improved Slide-Valve, of which the following is a full, clear, and exact description.

The invention relates to slide-valves composed of an inner valve for controlling the exhaust and of an outer valve for controlling the inlet of the motive agent.

The object of the invention is to provide a new and improved slide-valve which is simple and durable in construction, very effective and easy in operation, and permits of being run at a high rate of speed, preventing the unseating of the outer valve.

The invention consists of an outer valve provided with a loose top plate and an inner valve having play or lost motion in the outer valve, and provided with top ridges, on which rests the said top plate.

The invention also consists in certain parts and details and combinations of the same, as will be fully described hereinafter, and then pointed out in the claims.

Reference is to be had to the accompanying drawings, forming a part of this specification, in which similar letters of reference indicate 30 corresponding parts in all the figures.

Figure 1 is a sectional side elevation of the improvement, as applied. Fig. 2 is a like view of the same in a different position. Fig. 3 is a transverse section of the same on the line $\alpha\alpha$ of Fig. 1. Fig. 4 is an inverted plan view of the improvement. Fig. 5 is a plan view of the valve-seat, and Fig. 6 is a perspective view of the inner valve.

The valve-seat A is provided with the usual induction and eduction ports B and C and the exhaust-port D. On the valve-seat A is held to travel the slide-valve E, composed of an inner valve F and an outer valve G, which latter consists of an open rectangular frame, 45 on which fits a yoke H, to which is secured at one end the valve-stem I, connected with a suitable mechanism for moving the valve E forward and backward over the ports on the valve-seat A. In the open top of the outer valve G fits a plate J, preferably provided in

its ends and sides with spring packing-plates K, so as to form a steam-tight joint between the outer valve G and the said plate J. The inner valve F is provided on its top with longitudinally-extending ridges F', on top of which rests said top plate J. The ridges F' form spaces F² on top of the inner valve F, so that the motive agent can pass from one end of the valve to the other. The inner valve F is of the same width as the inside of the outer valve G, but the length of the inner valve is somewhat less, so as to form sufficient play or lost motion at either end, whereby the inner valve remains stationary during a certain time of the forward and backward stroke of the outer valve G, as hereinafter more fully described. The ends a and b of the outer valve G travel over the ports B and C, and in the sides c and d of the said valve, on the under side, are formed longitudinally-extending grooves e, registering at all times with openings D', leading into the exhaust-port D. The grooves e extend nearly throughout the length of the sides c and d, so that the underside of the said outer valve is connected by the said grooves with the exhaust-port D, and consequently the suction in the latter removes the pressure from the under side of the outer valve, so that an unseating—that is, a lifting of the valve 50 against the pressure of the live steam in the steam-chest—is prevented. At the same time if any steam from the steam-chest works under the outer valve G, it passes into the grooves e and to the exhaust-port D. This steam consequently does not exert an upward pressure against the valve G to unseat it.

When the valve E is in the position shown in Fig. 1, it is near the end of its right-hand stroke, and the motive agent passes from the steam-chest through the open port B into the left-hand end of the cylinder. The piston in the latter is then moved to the right in the direction of the arrow a', and when it is desired to cut off the valve-stem I travels in the inverse direction of the arrow a', so that the end a of the outer valve G passes over the port B and cuts it off from connection with the steam-chest. During this motion of the outer valve G the inner valve F remains sta- 1

tionary, and the motive agent in the right-hand end of the piston can fully exhaust through the entirely-open port C, the valve F, and into the exhaust-port D. When the end *a* 5 of the outer valve G is cut off from the port B, then the other end *b* comes in contact with the right-hand end of the inner valve F, as shown in Fig. 2, so that the latter is now moved with the outer valve in the inverse 10 direction of the arrow *a'*.

The ports C and D remain connected with each other until the piston has moved to the end of its stroke, so that a complete exhaust takes place in the cylinder. The right-hand 15 end of the valve F is then entirely across the port C, so that the end *b* of the outer valve G opens the port C to the steam-chest. Before this takes place the port B is connected by the inner valve F with the exhaust-port D, so that 20 when the piston commences its return-stroke the inner valve F fully connects the port B with the port D in the same manner as the ports C and D were formerly connected, as 25 illustrated in Figs. 1 and 2. The motive agent then enters through the port C into the right-hand end of the cylinder and forces the piston to make its return-stroke.

When the outer valve G is to cut off with its end *b* over the port C, then the valve-stem I 30 moves in the direction of the arrow *a'*, so as to move the outer valve G in the same direction, but the inner valve F remains stationary to fully exhaust the cylinder through the ports B and D. The valve F remains stationary 35 until the end *a* strikes against the left-hand end of the inner valve, and then moves it to the position shown in Figs. 1 and 2.

It will be seen that when the valve E is in the position shown in Fig. 1 and the outer 40 valve G travels in the inverse direction of the arrow *a'*, as above described, then the motive agent, entering through the port B, can pass, when the said end is in about the middle of the port, into the interior of the outer valve 45 G and through the spaces F^2 to the right-hand end of the inner valve F, so that a steam-cushion is formed around the inner valve F, whereby the force with which the end *b* of the outer valve G strikes the inner valve F is 50 somewhat broken.

It is understood that the inner valve F remains stationary on account of the motive agent surrounding the inner valve, as before described. The outer valve G can wear to 55 any extent without effecting the yoke H, carrying the valve-stem I, as the said yoke is free to slide upward on the outer valve. The wear of the inner valve F is taken up by the top plate J pressing on the ridges F' by the 60 force of the motive agent in the interior of the steam-chest.

The motive agent surrounding the inner valve F and pressing against the under side of the plate J is nearly equal in pressure to 65 the pressure of the motive agent in the steam-chest. Consequently the plate J is resting very lightly on the ridges F' of the inner valve, so

as to reduce the friction to a minimum, when the outer valve travels with the plate J and the inner valve remains stationary. At the 70 same time the plate J prevents the motive agent from rushing into the respective port B or C when the outer valve G moves away from the inner valve F.

Having thus described my invention, what 75 I claim as new, and desire to secure by Letters Patent, is—

1. A slide-valve comprising an outer valve actuated by the valve-gear and controlling the inlet-ports, an inner valve contained within 80 the outer valve for controlling the exhaust of the motive agent and adapted to be operated by the said outer valve, sufficient play or lost motion being had between the two valves, and a plate fitted into the open top of the outer 85 valve and resting on the top of the inner valve, substantially as shown and described.

2. A slide-valve comprising an outer valve operated by the valve-stem, a top plate held loosely in the said outer valve, and an inner 90 valve having lost motion or play within the outer valve, and provided with top ridges on which rests the said top plate, substantially as shown and described.

3. In a slide-valve, an outer valve actuated 95 by the valve-gear, and provided in the under side of its sides with grooves registering at all times with the exhaust-port, substantially as shown and described.

4. In a slide-valve, the combination, with an 100 outer valve controlling the inlet-ports, of a yoke fitted around the said outer valve and adapted to slide upward, a valve-stem held on the said yoke, an inner valve contained within the outer valve and operated by the 105 same, play or lost motion being had between the two valves, and a plate fitted in the open end of the said outer valve and resting on the top of the inner valve, substantially as shown and described.

5. In a slide-valve, the combination, with an 110 outer valve controlling the inlet-ports, of a yoke fitted around the said outer valve and adapted to slide upward, a valve-stem held on the said yoke, an inner valve contained 115 within the outer valve and operated by the same, play or lost motion being had between the two, ridges formed on top of the said inner valve, and a plate fitted into the top of the outer valve and resting on the said ridges, sub- 120 stantially as shown and described.

6. A slide-valve comprising an outer valve formed by an open frame, an inner valve controlled by the said outer valve, and provided in its under side with an exhaust-cavity and 125 on its top with ridges, and a plate fitted into the open top of the outer valve, substantially as shown and described.

7. A slide-valve comprising an outer valve formed by an open frame having in the bottom of its sides grooves registering at all times with the exhaust-port, an inner valve controlled by the said outer valve, and provided in its under side with an exhaust-cavity and 130

on its top with ridges, and a plate fitted into the open top of the outer valve, substantially as shown and described.

8. In a slide-valve, the combination, with an outer valve controlling the inlet-ports and having part of its under surface exposed to the exhaust-port, so as to be held on its seat by the pressure of the motive agent inside of the chest, of an inner valve controlling the exhaust and contained within the said outer valve, and having lost motion or play with the latter, the said inner valve being held on its seat by the pressure of the motive agent within the chest, substantially as shown and described.

15 9. In a slide-valve, the combination, with an outer valve controlling the inlet-ports and hav-

ing in its under side grooves registering at all times with the exhaust, so as to permit steam passing under the said valve to escape through the exhaust, of an inner valve controlling the exhaust of the motive agent and contained within the said outer valve, and having lost motion within the latter, and a plate held loosely in the top of the outer valve and resting on top of the said inner valve, so as to hold the latter on its seat by the pressure of the motive agent inside the chest, substantially as shown and described.
